United States Patent Office.

GEORGE WALTERS AND THOMAS SHAFFER, OF PHOENIXVILLE, PENNSYLVANIA.

Letters Patent No. 75,712, dated March 17, 1868.

IMPROVED FAGOT FOR BEAM.

The Schedule referred to in these Letters Patent and making part of the same.

TO ALL WHOM IT MAY CONCERN:

Be it known that we, GEORGE WALTERS and THOMAS SHAFFER, of Phoenixville, Chester county, Pennsylvania, have invented an Improved Pile or Fagot for Wrought-Iron Beams or Girders; and we do hereby declare the following to be a full, clear, and exact description of the same.

Our invention consists of a pile or fagot, (for wrought-iron beams or girders,) composed of a solid bar or bars, having a rib confined between other bars by riveting the latter to intervening bars, which are, together, less in thickness than the said rib, all as described hereafter, the several parts composing the pile being thus held together while subjected to heat in the furnace, and forming, when rolled, a compact and rigid beam or girder.

In order to enable others skilled in the art to make and apply our invention, we will now proceed to describe the mode of carrying the same into effect, reference being had to the accompanying drawing, which forms a part of this specification, and in which—

Figure 1 is a transverse section of our improved pile or fagot for wrought-iron beams or girders.

Figure 2, a side view of part of the pile.

Figures 3, 4, and 5, sections of piles for beams of different forms, and

Figure 6 a section representing a modification of our improvement.

On reference to figs. 1 and 2, A and A' represent two bars, on one face of each of which, midway between its opposite edges, is formed a rib, a, the ribs a of the two bars being confined by and between the two bars b and b', between which intervene the two bars c and d, the arrangement of the several bars in respect to each other being clearly indicated in fig. 1.

The thickness of the two bars c and d combined is somewhat less than the width of the rib, so that, on securing the bars b b', c, and d together by rivets, e e, the outer bars, b b', will have a gripping effect on the ribs, and thus hold the whole of the bars together in a pile while it is being subjected to a welding-heat in a furnace prior to its conversion into an H-beam by the action of suitable rolls. In fig. 3 the bars are arranged and secured according to our invention for a pile to be converted into a T-beam. In fig. 4 the pile is arranged for a cruciform beam or girder, and in fig. 5 for an L-beam.

It is not essential that the web of the beam should be composed of the exact number of bars shown, as there may be two or more gripping-bars, b or b', on each side of the rib a, and any desired number of intervening bars, c d; or, the web for beams of great depth may be composed of a number of bars, arranged and secured together and to the rib a in the manner clearly illustrated by fig. 6, in any of the cases the beam, when rolled, being of the most solid and rigid character.

We do not desire to claim broadly a pile composed of a bar having a rib arranged between bars composing the web for a beam or girder; but

We claim as our invention, and desire to secure by Letters Patent—

A pile or fagot, (for wrought-iron beams or girders,) consisting of a solid bar or bars, A, having a rib, a, gripped by and between bars b and b', secured by transverse rivets to intervening bars, which are, together, less in thickness than the said rib a, all as set forth, for the purpose specified.

In testimony whereof, we have signed our names to this specification in the presence of two subscribing witnesses.

GEORGE WALTERS,
THOMAS SHAFFER.
